US00D473800S

(12) **United States Design Patent** (10) Patent No.: **US D473,800 S**
(45) Date of Patent: ** Apr. 29, 2003

(54) **WATCH AND WATCH COMPONENTS**

(75) Inventors: **Hans Karsten Moritz**, Foothill Ranch, CA (US); **Christopher Petrillo**, Irvine, CA (US); **James H. Jannard**, Spieden Island, WA (US)

(73) Assignee: **Oakley, Inc.**, Foothill Ranch, CA (US)

(**) Term: **14 Years**

(21) Appl. No.: **29/165,883**

(22) Filed: **Aug. 15, 2002**

(51) LOC (7) Cl. **10-02**

(52) U.S. Cl. **D10/32**

(57) **CLAIM**

The ornamental design for a watch and watch components, as shown and described.

DESCRIPTION

FIG. 1 is a front perspective view of an alternate embodiment of the watch and watch components of the present invention;

FIG. 2 is a front elevational view thereof;

FIG. 3 is a rear elevational view thereof;

FIG. 4 is a top plan view thereof;

FIG. 5 is a bottom plan view thereof;

FIG. 6 is a right-side elevational view thereof; and,

FIG. 7 is a left-side elevational view thereof.

The broken line showings of logos, wristband, and knobs, where used, are for illustrative purposes only and form no part of the claimed design.

1 Claim, 4 Drawing Sheets
